UNITED STATES PATENT OFFICE

2,196,104

PROPELLER

William G. Corson, Akron, Ohio

Application June 18, 1936, Serial No. 85,927

3 Claims. (Cl. 170—151)

The present invention relates to a rotary propeller or fan construction consisting of component parts wherein the blades are mounted on each component part on lines that are off center with respect to each other.

Other objects and advantages will become apparent as the description proceeds in which:

Figure 1 is an end view of one component part of the propeller,

10 Figure 2 is an end view of the other component part,

Figure 3 is an end view showing one component part provided with six blades with the blades positioned off center lines of the hexagonal center point,

15 Figure 4 is an end view of the two component parts in alignment and showing the relative positions of the blades of the respective parts in respect to the axes,

20 Figure 5 is a view looking at right angles to Figure 4,

Figure 6 is a view taken on an angle of 180° of Figure 5 when eccentric is changed,

25 Figure 7 shows a component member provided with more than one blade on its arms, and

Figure 8 shows a curved blade adapted for use in the present invention.

In the drawing, the component parts, 2 and 3, forming the assembled propeller unit, are each

30 provided with blades A and B mounted on the ends of arms 4 and 5, respectively. The arms 4 and 5 are one-half the width of the blades A and B from the center of the component parts.

The arms 5 carrying blades B are longer than

35 the arms 4 by one-half the width of the blades. The arms 4 and 5 are mounted, on the parts 2 and 3, on the opposite sides to the relative positions necessary to allow the two component parts

40 2 and 3 to rotate freely when assembled and the component parts 2 and 3 are made identical but

45 take the positions shown, in Figures 4 to 6 inclusive, when inverted with respect to each other and assembled. It is to be noted that the centers C and D of the two component parts are spaced apart one-half the width of a blade.

45 In the showing of Figure 3, there is provided a component part having six blades instead of four and it is to be noted that the blades are positioned off center lines as illustrated by the hexagon construction. In Figure 4, the two compo-

50 nent parts having six blades are shown in alignment. The relative position of the blades with respect to the centers, and with respect to each component, will become readily apparent. In

55 this showing, the blades A and B at the bottom

are in the same horizontal plane while the blades A and B, at the top, are each in its own horizontal plane, and the position of the other blades are shown in their respective planes about the centers. The number of blades that may be placed 5 on each component part is not restricted in number but each component part should contain the same number of corresponding blades.

The line of force, as well as the rotation of the component parts, is controllable by means to be 10 subsequently described and the line of force is capable of being changed anywhere along the circumference of the travel of the blades as to be hereinafter set forth. When applying mechanical power in any conventional manner to 15 the blade shaft, the direction of force may change from the top of the component parts, as shown in Figure 5, to the bottom of said component parts, as shown in Figure 6, by operating the lever 6 to change the position of the eccentric device subsequently to be described. However, while the line of force is changed by such an operation, the rotation of the component parts is not changed but continues the same regardless of what angle along the circumference the line 20 of force is presented to the blades of the component parts. When a natural fluid force is applied to the blades, the line of force is shown at Figure 25 4 as being at the top and will cause rotation in one direction. However, by operating the eccentric 180 degrees, as shown in Figure 6, the line of force is changed to the bottom and will cause a rotation of the blades and component parts in the opposite direction.

In Figure 4, the force lines are clearly shown. 35 The width of areas S—T—U—V are greater than the width of areas W—X—Y—Z and the angle of contact on the opposite blades are approximately equal. It is, therefore, apparent that a force applied to the wheel assembly and as shown by 40 these force lines, will rotate the component parts in the direction of the arrow in the upper left hand side. However, if the eccentric is rotated one-half turn, the blades assume a position relative to each other as clearly shown in Figure 6, 45 which would result in the rotation of said component parts in an opposite direction to that just described. When the blades are in the same plane, the blade that follows is useless in giving or receiving power.

If an outside power is applied to cause the component parts to rotate, then the force or flow of pressure from the upper force areas in Figure 4 would be greater than that given in the lower force areas; but as shown in Figure 6, if the rela- 55

tive positions of the component parts are changed, the greater flow would be in an opposite direction, or in whatever direction the eccentric is set by the operation.

- 5 The eccentric means for changing the relative positions of the component parts with respect to each other comprises a universal joint 7, secured to the inside center of the component part 3, while on the inside center of component part 2 10 there is provided a universal joint 8 and a connecting rod 9 between the two universal joints. Between a standard 10 and the component part 2, is mounted the eccentric operating lever 6, which has its center on the center line of one of the 15 component parts. The center of the component part 2 is mounted on this eccentric lever 6 at 12, which point is distant from the center line D of component part 3 by one-half the width of a blade. By moving the eccentric lever 6 upon its 20 axis at the center line D, the relative position of the point 12 or the center line of component part 2 will change. While I have shown, for the purpose of illustration, a standard for mounting the component parts 2 and 3, and the universal 25 connection so that these parts will rotate simultaneously and in agreed positions, other mechanisms may be used to rotate the component parts 2 and 3 simultaneously and in agreed positions.
- 30 The change of direction of the force is accomplished by rotating the eccentric lever 6 to change the relative position of the blades A and B on the component parts and not by stopping and changing the direction or rotation of the wheel. Nor 35 is it necessary to change the speed of rotation to obtain a different direction of force. Some of the many uses for which this invention may be adapted are such as airplane and airship propellers, windmills, ventilators, blowers, boat propellers, etc.
- 40 While I have shown and described one specific embodiment of the invention, it will be understood that I do not wish to be limited exactly thereto, since various modifications may be made without

departing from the scope of the invention as defined by the following claims.

I claim:

1. A rotating propeller comprising a shaft, complemental blade supporting means mounted on 5 said shaft, a plurality of blades mounted on each of said complemental supporting means cooperating with each other, one of said complemental blade supporting means being eccentrically mounted on said support with respect to the other 10 blade supporting means so that the coacting blades overlap each other at one point and are in alignment at a point diametrically opposite the point of overlap.

2. A rotating propeller comprising a shaft, complemental blade supporting means mounted in inverted positions with respect to each other on said shaft and coacting blades mounted on said complemental supporting means, one of said complemental blade supporting means being eccentrically mounted on said shaft with respect to the other blade supporting means so that the coacting blades overlap each other at one point and are in alignment at a point diametrically opposite the point of overlap, and means for rotating the 25 eccentric to change the direction of rotation of the propeller.

3. A rotating propeller comprising a shaft, complemental blade supporting means mounted in inverted positions with respect to each other 30 on said shaft and coacting blades mounted on said complemental supporting means, one of said complemental blade supporting means being eccentrically mounted on said shaft with respect to the other blade supporting means so that the coacting blades overlap each other at one point and are in alignment at a point diametrically opposite the point of overlap and means for rotating the eccentric to change the position of the blades on said eccentrically mounted supporting means 35 relative to the blades on said other supporting means so as to change the direction of force of said propeller.

WILLIAM G. CORSON.
